Section 1, Public Law 690, August 8, 1946
 Patent expires November 17, 1964

5 Claims. (Cl. 248—281)

1

This invention relates to an improved mounting, more particularly for inspection lamps, and has for its chief object to provide an improved and simple mounting which will enable the lamp to be quickly and easily arranged to throw the light on any desired point within its range and to stay put in any given position, and which will, furthermore, at all times, be balanced and stable.

According to the present invention, the lamp or other article is carried at one end of a first parallel linkage system, the other end of which is connected to a second parallel linkage system which, in turn, is connected at its further end to a base or support and the whole is balanced by means of a weight carried by one link (or by an extension of one link) of a third parallel linkage system, the inclination of one pair of links of the said third parallel linkage system being controlled by movement of the first parallel linkage system, and the inclination of the other pair of links of the third parallel linkage system being controlled by movement of the second parallel linkage system.

Conveniently all three of the parallel linkage systems have a common pivot point, adjacent links of the third parallel linkage system at this point being formed one by an extension of one of the links of the first parallel linkage system, and the other partly of that link of the second parallel linkage system which extends down to the base or support and partly by an extension of the same beyond the pivot.

Preferably the parts are so proportioned that an imaginary line adjoining the centre of gravity of the lamp or other article and the centre of gravity of the counter-weight will at all times pass through the point at which the link common to the second and third parallel linkage systems is pivoted to the base or support.

In order that this invention may be the more clearly understood and readily carried into effect, I will proceed to describe the same with reference to the accompanying drawings, which illustrate by way of example one convenient embodiment of the present invention, and in which:

Figures 1 and 2 are somewhat diagrammatic views showing the relationship of the various parallel linkage systems and the way in which they co-operate with one another.

Figure 3 is a perspective view of an inspection lamp mounting according to the present invention, and

Figures 4 and 5 are respectively cross-section through and end elevation of a detail of construction more fully described hereinafter.

2

Referring now to the drawings, the inspection lamp mounting therein illustrated comprises a support 10 which may, if desired, be pivotally mounted as at 11 so that it can rotate on a vertical axis on a base 12, said support 10 extending upwardly and having an upwardly and rearwardly inclined portion 10a. Pivotally mounted at spaced points on this inclined portion of the support are the members 13, 14 of the second parallel linkage system above-mentioned. The upper ends of these links 13, 14 are pivoted at 13a, 14a to a triangular member 15 having a front face to which are pivotally connected at spaced points 13a, 16a, the forwardly extending links 16, 17 of the first-mentioned parallel linkage system. Both parallel linkage systems are preferably duplicated and the lamp 20 may be mounted between the front ends of the first parallel linkage system in the manner described in my prior British Patent No. 559,006, so that the advantages of the mounting described in that specification are obtained. Any other method of mounting the lamp, with or without friction-tight holding means may, of course, be employed without departing from the scope of the present invention.

Now it will be appreciated that with such an arrangement of two parallel linkage systems 13, 14 and 16, 17, the lamp 20 may be moved to any desired position within the range of the two parallel linkage systems, but the problem is to counter-balance the weight of the lamp at the widely different distances from the support 10 at which it can be disposed. This difficulty is overcome, according to the present invention, by the aid of a single counter-balance weight and a third parallel linkage system.

The rear end of the lower link 17 of the first parallel linkage system 16, 17 and the upper end of the front link 13 of the second parallel linkage system 13, 14 are arranged to have a common pivot point 13a on the triangular member 15, and the third parallel linkage system is established as follows: the top link 17a by an extension of the bottom link 17 of the first parallel linkage system 16, 17 beyond the pivot point 13a, the front link, in part, by the front link 13 of the second parallel linkage system 13, 14 and, in part, by an extension 13b of the same beyond the point 21 at which it is pivoted to the support 10, and the back and bottom links by links 22, 23 corresponding respectively to the front and top links 17a and 13, 13b, but forming no part of the other parallel linkage systems. The bottom link 22 is extended rearwardly, as at 22a, and at the appropriate

point is provided with a counter-balance 24 of the required weight.

With such an arrangement inclination of the top and bottom links 17a and 22, 22a, of the third parallel linkage system will be controlled by movement of the first parallel linkage system 16, 17, and the inclination of the front and back links 13, 13b and 23, will be controlled by movement of the second parallel linkage system 13, 14 and the position of the counter-weight 24 and, more particularly, the distance from the front lower pivot 21 of the second parallel linkage system at which it lies will depend upon the position of the lamp. This will be appreciated more clearly on reference to Figures 1 and 2, the two positions of Figure 1 showing the way in which the first parallel linkage system 16, 17 controls the position of the links 17a, 22, 22a, whilst Figure 2 shows how the inclination of the front and back links 13, 13b and 23 is controlled by movement of the second parallel linkage system 13, 14. The counter-balancing moment, due to the counter-balance weight 24, will be small when the lamp is disposed near the base (the full line position of Figure 1), and will be increased as the lamp is moved farther away from the base or support, as shown in broken lines in Figure 2. By suitably proportioning the lengths of the links of the third parallel linkage system and the position at which the counter-balance is positioned on the extension of the bottom link, the mounting can be so arranged that the weight of the lamp is exactly counter-balanced in all positions without the aid of friction washers at the joint, or at least with only very little friction at the joints. The lamp may thus be freely moved with the least energy to any desired position, will stay put in that position and, furthermore, will be quite stable in that position, there being no tendency to overbalance however far the lamp be stretched out away from the base or support.

It will be found that with the parts so proportioned and arranged a complete counter-balance is obtained at all times, an imaginary line (the chain lines A in Figures 1 and 2) joining the centre of gravity of the lamp with the centre of gravity of the counter-balance weight will pass through the front pivot of the second parallel linkage to the base so that the mounting becomes in effect a simple counter-balanced lever of the first order whilst, at the same time, permitting the lamp to be positioned at any point within the combined range of the first and second parallel linkage systems.

With the construction above described a certain amount of whip may develop in the mounting, particularly if the first and second-mentioned parallel linkage systems are long. In order to overcome this, one of the links may be made of flattened tubular form, as shown at 16b in the detail views of Figures 4 and 5, and may be arranged closely to surround the opposite link 17 of the parallel linkage system in question except at its ends (see Figure 5). This will overcome any whip in the mounting as will be appreciated.

Although the present invention has been described more particularly as a mounting for inspection lamps it will be appreciated that it is equally applicable to the mounting of other articles such as shaving and other mirrors.

I claim:

1. A mounting for supporting an inspection lamp, which comprises, in combination: a supporting base a first parallel linkage system, said

parallel linkage system being adapted, at one end thereof, to support said inspection lamp; a second parallel linkage system connected at one end thereof to the end of said first parallel linkage system which is remote from said end thereof at which said inspection lamp is supported, and the other end of said second parallel linkage system being connected to said supporting base; a third parallel linkage system connected at one end to said first and second parallel linkage systems, said third parallel linkage system comprising two pairs of links, one pair thereof being connected at one end of said first pair of links to said first parallel linkage system, and the second pair thereof being connected at one end of said second pair of links to said second parallel linkage system; and a counterbalancing weight carried by said third parallel linkage system at the ends of the said pairs of links thereof remote from the ends to which said first and second parallel linkage systems are connected, the inclination of one pair of links of said third parallel linkage system being thus controlled by movement of said first parallel linkage system, and the inclination of the other pair of links of said third parallel linkage system being thus controlled by movement of said second parallel linkage system.

2. A mounting for supporting an inspection lamp as defined in claim 1, which includes a triangularly-shaped member forming one end link of both said first and second parallel linkage systems, said first parallel linkage system and said second parallel linkage system being both connected to said triangularly-shaped member, said connection between one end of said first parallel linkage system and one end of said second parallel linkage system, thus being accomplished by said connections of both to said triangularly-shaped member, and said two parallel linkage systems which are thus connected having one pivot point in common, said pivot point in common being positioned adjacent one corner of said triangularly-shaped member.

3. A mounting for supporting an inspection lamp as defined in claim 1, wherein all three of said parallel linkage systems have a pivot point in common, wherein the links of one of the pairs of links of said first parallel linkage system are provided with extensions at one end thereof, and wherein the links of one of the pairs of links of said second parallel linkage system are provided with extensions at one end thereof beyond that point at which said links are connected to said supporting base, the pairs of links of adjacent links of said third parallel linkage system being formed, as to one pair, by said extensions on said links of said first parallel linkage system and as to said second pair partly by said links of said second parallel linkage system which are connected to said supporting base, and partly by said extensions thereof beyond said supporting base.

4. A mounting for supporting an inspection lamp as defined in claim 3, wherein said parallel linkage systems and said counterbalancing weight are so arranged and proportioned that an imaginary line joining the center of gravity of the inspection lamp supported by said first parallel linkage system and the center of gravity of said counterbalancing weight passes through the point at which said link which is common to said second and said third parallel linkage systems is connected to said supporting base, for all positions of said parallel linkage systems and said supported inspection lamp.

5. A mounting for supporting an inspection

lamp as defined in claim 4, wherein one long link of at least one of said parallel linkage systems is formed throughout the major portion of its extent in flattened tubular shape, and wherein said link of flattened tubular shape closely surrounds the opposite long link which, together with said link of flattened tubular shape, comprises a pair of parallel links.

F. G. HORSTMANN.
